UNITED STATES PATENT OFFICE

2,597,166

END BRACKET FOR UTILITY STANDS

Jack W. Murray, Salem, Wis.

Application February 18, 1949, Serial No. 77,215

1 Claim. (Cl. 311—105)

1

This invention relates to typewriting stands, utility stands and devices of like character, and has for its general aim the provision of a novel and improved structural assembly of parts so designed and related that the stand may be shipped in a disassembled or "knocked-down" condition, yet may be quickly and easily assembled by the purchaser, and when assembled will be strong, rigid, and yet of neat and pleasing appearance.

It has been common prior practice to construct small stands suited to supporting a typewriter, adding machine or the like by providing a top panel with tubular legs secured to the underside of the panel and extending downwardly to the floor. Ordinarily braces are secured between the legs to give the structure rigidity, and it is common practice to provide a pair of hinged end panels with jointed supports extending from the underside of each end panel to one of these braces.

It has been found that while this type of construction is reasonably satisfactory after assembly, yet it is disadvantageous from a merchandising standpoint by reason of the fact that it is not ordinarily advisable to ship the stands to the dealer or user in completely assembled condition, yet if shipped "knocked-down," the units are somewhat difficult to assemble and frequently confuse the purchaser who is often unfamiliar with the manner in which the various parts are supposed to be put together. It is therefore the primary aim of the present invention to depart from these prior teachings and to provide an improved type of stand wherein the legs are not secured to the top panel directly, but are instead secured to a pair of end brackets, each of which are mounted on the under surface of the top panel. According to the present invention, the legs support the brackets and the brackets in turn support the panel. By this expedient the brackets and top panel may be permanently assembled at the factory and if the stand is provided with hinged end panels, as is customary, these may be hinged in place and folding supports assembled between the end panels and the end brackets so that they may be raised or lowered as desired. With such an assembly it is entirely feasible to assemble all parts, except the legs themselves, at the factory. Thus the unit requires a minimum of shipping space, yet may be put in use by merely mounting the legs thereon.

Referring now to the drawings of this specification in which a present preferred embodiment of the invention is illustrated.

Figure 1 is a perspective view of a typing or utility stand according to these teachings;

Figure 2 is a perspective view of a pair of leg frames and end brackets, as here utilized, show-

2

ing the manner in which these parts fit together; and

Figure 3 is a detail sectional view taken substantially on the plane of the line 3—3 of Figure 2.

The stand has a top panel 10 which is ordinarily of rectangular shape and may be provided with a pair of end panels 11 and 12 hinged to the panel 10 along their adjoining edges. The top panel 10 has a pair of end brackets generally designated as 13 secured to its undersurface near its opposite ends. The end brackets 13 each consist of a vertical end plate 14 integral with and extending between a pair of corner plates 15. The end and corner plates are provided with flat flanges 16 and 17 on which the top panel 10 is mounted. The corner plates 15 have inwardly extending curved flanges 18 and the end plate 14 may have a bottom flange 19 and, if desired, may be ornamented and reinforced by forming as indicated at 20.

The legs of the stand are preferably tubular, and as shown comprise two opposite leg frames, each consisting of a horizontal bar 21 with downwardly curved corner portions 22 at each end terminating in integral legs 23. These may be provided with casters 24, if desired, and may be offset outwardly at 25 to increase the stability of the unit.

The stand is assembled at the factory by mounting the end brackets 13 on the underside of the top panel 10, hinging the panels 11 and 12 in position and mounting jointed supports 26 between fittings 27 on the underside of the end panels and similar fittings 28 secured to the end plates 14 of the bracket. These may be fastened by screws or rivets entering the perforations 29. The stands may be shipped in this partially assembled condition with a considerable saving in space required, but it is to be noted that the panels, brackets and hinged supports are all permanently joined to each other and in operating condition. Thus, when the unit is received by the purchaser it is only necessary to position the leg frames against the inner side of the curved flanges 18 and secure them by the machine screws 30 inserted through openings provided for the purpose. There is no possibility for confusion as to the manner in which the parts should be assembled. Also, since the unit consists of only three separate parts, there is little likelihood of any of the parts being overlooked or mislaid in the course of unpacking. Moreover, when the stand is assembled it is of neat appearance and is structurally stronger and more rigid than prior types.

Having thus described the invention, I claim:

An end bracket for a utility table having a top panel with a pair of double leg frames each consisting of a horizontal top bar with downwardly

curved corner portions terminating in downwardly extending legs; said end bracket consisting of a generally rectangular end plate vertically disposed under the top panel with a horizontal flange along the upper edge of said end plate bearing against the under surface of the panel and with additional integral reinforcing means extending across the end plate below said flange, each end of the end plate having a curved portion extending into and integral with a pair of identical and opposite corner plates lying in generally parallel planes with each other but spaced apart, said corner plates each having a horizontal inwardly extending flange along the upper edge thereof and a curved flange partially encircling one of the curved end portions of each of the double leg frames, the lowermost end of each of said curved flanges lying substantially parallel with but spaced from the end plate and each of said flanges extending upwardly and outwardly therefrom in a curve terminating in a generally horizontal portion spaced below the end of the horizontal flange of said corner plate, together with means on said bracket for securing it to the leg frames of the table.

JACK W. MURRAY.
